UNITED STATES PATENT OFFICE

2,675,840

EXTENSION LEVER FOR RATCHET BIT
BRACES

Orme C. Daiber, Seattle, Wash.

Application February 23, 1949, Serial No. 77,753

2 Claims. (Cl. 145—66)

1

My present invention relates to boring tools and, more particularly, to an extension lever for ratchet bit braces.

My invention consists of providing an easily applied and secure extension lever for increasing the sweep or mechanical advantage of an ordinary carpenter's brace, or bit-stock, and is particularly useful in the boring of large holes. The average carpenter, having a reasonably complete kit of tools, will usually have a brace of small sweep for use with the smaller diameter wood bits, and then a large sweep brace for use with the larger bits. However, there are many occasions when even the large sweep brace is not adequate to conveniently turn the ordinary wood bit of, say, one inch diameter in firm wood. Moreover, a carpenter is quite often required to drill holes considerably larger than one inch, and he normally will employ what is known as an expansion bit wherein an adjustable cutter can be set to cut the desired diameter up to, say, three inches, and the shank of the expansion bit is provided with the ordinary lead screw to cause the cutter to bite into the wood. When drilling such a large hole, considerable difficulty is experienced, and it is under such conditions that my extension lever, which can be quickly attached to the brace, gives a mechanical advantage of at least double that normally available in the normal sweep handle of the brace.

The principal object of my present invention, therefore, is to provide an extension handle for carpenter's bit braces.

A further object of my invention is to provide an extension handle for bit braces which greatly increases the mechanical advantage so that the effort of turning the brace will be greatly reduced.

A further object of my present invention is to provide an extension handle for boring braces that can be quickly secured in place without any separate clamps or other screw adjusted means.

A further object of my invention is to provide a brace extension lever which can be very cheaply constructed and can be sold at such low enough price that it will be generally available to workmen.

A further object of my invention is to provide a brace extension lever which is fabricated from sheet metal so that it will be light in weight and will be durable against breakage.

Further objects, advantages and capabilities will be apparent from the description and disclosure in the drawings, or may be comprehended or are inherent in the device.

2

In the drawings:

Figure 1 is an elevation showing a typical ratchet brace with my extension lever secured in operating position thereon.

Figure 2 is a fragmentary, perspective view showing the attaching end of my extension handle.

Figures 3 and 4 are cross-sectional views taken along respectively numbered lines on Figure 1.

Referring more particularly to the disclosure in the drawings, my extension handle consists of a gripping or clamping portion 10, a securing or positioning portion 12, and handle portion 15. The gripping portion 10 is illustrated in cross-section in Figure 4. It consists of a generally U-shaped member formed of sheet metal with the diameter of the curved portion of the U substantially the diameter of the brace stock with which it is to be used. This causes the U-shaped portion of my tool to rest securely upon the upper brace arm, as 14, and to be secured in a snap-on relationship by a plurality of inwardly directed indentations, as 16 and 17. This portion of the tool, being U-shaped in form, is relatively strong, and it also is, therefore, well able to impart the turning effort applied on handle 15 to the brace itself.

In order to prevent longitudinal movement of clamp portion 10 on the brace member 14, I have provided an outwardly extending arm, as 20, which terminates in a U-shaped stirrup member 22. This stirrup member is U-shaped and again has a diameter of curvature substantially the same as the stock 24 of the brace it is to be used with.

That portion of my extension handle that extends out beyond the brace handle 26, I prefer to form as a round or oval section, so that maximum pressure can be applied to it without either distorting the handle itself or causing undue pressure at any part of the workman's hand. Following this same plan, I prefer to slit the end of the tubular portion or handle thus formed in a plurality of slits 28, and then fold the metal over so that a smooth closed end 30 is obtained.

Method of use

In using my extension lever on a carpenter's brace, it is preferred to employ the type of brace having a ratchet mechanism, as at 32, to the end that the auger or drill bit can be turned by an oscillating movement of handle 26. It will be understood, of course, that the extension handle could be used on a fixed brace; however, it could not be employed to advantage. The handle is

put in place on a brace by engaging stirrup member 22 on shank 24 with the clamp portion 10 of the extension handle substantially parallel to that portion, as 14, of the brace with which it is to be engaged. The clamp is then engaged with member 14 by a marked downward pressure as viewed in Figure 1. This will cause the U-shaped gripping or clamping member to straddle bar 14, and to be forced down so that indentations 16 and 17 are below the center of bar 14. In this way, a firm grip is obtained and the extension handle is worked in an oscillating movement. The ratchet 32, in effect, converts this intermittent action into rotary turning of the bit chuck and, thereby, to the bit held in the chuck.

Under certain conditions, it is desirable not to use stirrup 22 but to employ indentations as 18 so placed as to engage handle bar 27 or the curve at the junction of bar 27 and the upper sweep bar 14. This arrangement substitutes for stirrup 22, although not quite as effective in preventing longitudinal movement of the clamp member on bar 14.

It is believed that it will be clearly apparent from the above description and the disclosure in the drawings that the invention comprehends a novel construction of an extension lever for ratchet bit braces.

Having thus disclosed the invention, I claim:

1. An extension handle for a carpenter's brace, comprising: a single sheet of metal bent to form a stirrup like arm at one end, a clamping intermediate section and a handle portion at the other end in integral connection, said intermediate section being elongated and of considerable extent and having an inverted U-shaped outline in transverse cross-section and said intermediate section having inwardly directed indentations in its sides forming projections on the inner side surfaces for engaging a brace upper sweep bar, positioned in said intermediate section, below its center and said sheet having sufficient resiliency to permit spreading of the sides of said intermediate section in insertion and removal of the sweep bar in a lateral direction, said stirrup like arm being formed by an extension of said inter-

mediate section directed upward therefrom at a sharp angle and terminating in an end arc shaped and open towards one side of said handle adapted to clamp the stock of such brace with the lips of the arc extending to the sides of the arc sufficient distance to abut the stock to prevent movement of the intermediate section longitudinally of the sweep bar; and said handle portion being formed with the sheet bent into an annular outline in transverse cross-section with the edges of the sheet meeting on the underside of the handle and with the extreme end rounded.

2. An extension handle for a carpenter's brace, comprising: a unitary metal body forming a stirrup like arm at one end, a clamping intermediate section and a handle portion at the other end, said intermediate section being elongated and of considerable extent and having an inverted U-shaped outline in transverse cross-section and said intermediate section having means for engaging a brace upper sweep bar, positioned in said intermediate section, below its center to secure the sweep bar against movement laterally of the intermediate section, said stirrup like arm being formed by an extension of said intermediate section directed upward therefrom at a sharp angle and terminating in an end arc shaped and open towards one side of said handle adapted to clamp the stock of such brace with the lips of the arc extending to the sides of the arc sufficient distance to abut the stock to prevent movement of the intermediate section longitudinally of the sweep bar; and said handle portion being formed with an annular outline in transverse cross-section and with the extreme end rounded.
